REGENERATION OF SPENT DOCTOR

Chester L. Read, Westfield, and Thomas J. Broidrick, Orange, N. J., assignors to Standard Oil Development Company, a corporation of Delaware and Bayway Engineering Company, a corporation of Delaware

Application October 3, 1935, Serial No. 43,325

4 Claims. (Cl. 23—51)

This invention relates to improvements in the regeneration of spent doctor solution, especially spent doctor solution that had been used in sweetening gasoline or naphtha, etc.

5 Most of the gasoline and naphtha marketed is finished by doctor sweetening. Doctor sweetening consists essentially in converting the mercaptans to lead mercaptides by treating with a sodium plumbite solution followed by the conversion of the mercaptides to disulfides and lead sulfide on addition of sulfur. Some of the doctor solution readily separates from the oil as a clear solution while another fraction of the doctor solution separates from the major portion of 10 the oil in the form of an emulsion consisting of about 25 to 85% of naphtha, 20 to 50% of spent doctor solution, and 5 to 20% of lead sulfide.

15 It was the practice formerly when it was desired to regenerate the doctor solution to blow the entire spent doctor solution with air, whereby the more volatile naphtha portions were completely lost after prolonged blowing with air, the lead sulfide converted to lead oxide and regenerated sodium plumbite solution recovered. A 20 more recent practice is to first separate out the naphtha by means of a centrifuge and blow the residue consisting of lead sulfide and spent doctor solution with air to regenerate sodium plumbite solution. A disadvantage in this process is 25 in the length of time required to regenerate the spent doctor solution.

30 An object of this invention is to provide an improved method of regenerating spent doctor solution in a short period of time.

35 This and other objects of the invention will be understood on reading the following description with reference to the accompanying drawing:

Fig. I is a somewhat diagrammatic representation in elevation of an apparatus adapted for the practice of the improved process of the invention;

40 Fig. II is an elevation partly in section of one of the forms of apparatus suitable for use in the apparatus illustrated in Fig. I;

Fig. III is a view of the rotor in the apparatus illustrated in Fig. II;

Fig. IV is a view of the stator in the apparatus illustrated in Fig. II; and

50 Fig. V is a downward view of the apparatus illustrated in Fig. II, without the motor, rotor and stator.

Referring to the drawing, numeral 1 denotes a pipe provided with valve 2 through which the 55 spent doctor solution together with lead sulfide

(after the naphtha has been removed) is passed into the lower part of a mechanical mixer 3 into a rotor 4. In the mechanical mixer 3, the rotor 4 is revolved by means of electric motor 5. This rotor is revolved in the space enclosed by the 5 stator 6, both the rotor and stator being in turn enclosed by a cylinder 7 which is enclosed on the bottom with a plate 8, and may also be enclosed on the top with a plate 9.

The spent doctor solution together with the 10 lead sulfide, by means of the revolving rotor 4 is brought in intimate contact with air or other oxygen containing gas passing through openings (not shown) in the plate 9 into the space enclosed by the stator 6. The rapid movement 15 of the spent doctor solution by means of the rotor 4 creates a partial vacuum which causes a large volume of air to rush into the rotor. The in-rushing air is there thoroughly dispersed through the spent doctor solution in the form 20 of fine bubbles and regenerates the doctor solution. When the spent doctor solution is subjected to this mechanical stirring, the fine bubbles of air are dispersed through this solution, and at times a considerable quantity of foam 25 may be produced. The foam may be several feet in depth and is removed by means of spillway 11, together with regenerated doctor solution, through an opening in the side of cylinder wall 7.

Spillway 11 empties the regenerated doctor 30 solution and the foam into settling tank 12, which is provided with a cone-shaped bottom 13. The foam readily breaks and two layers are 35 formed, one of regenerated doctor solution and the other of lead sulfide that has been carried over with the regenerated doctor solution and the foam. This cone-shaped bottom 13 is provided with an outlet pipe 14, through which, by means of pump 15, the lead sulfide, after settling out, is returned to the mechanical mixer 3. 40

As the spent doctor solution may not be all regenerated on passing through the mechanical mixer 3 the first time, the spent doctor solution in the mechanical mixer 3, which has not been withdrawn or converted into foam, flows through 45 openings 16 into a space 17 enclosed by bottom plate 8 and bottom enclosure 18. There this spent doctor solution is again repassed through the rotor 4 and mixed with air.

Spent doctor solution also varies as to the 50 quantities of oxygen required for regeneration. Therefore, the process may be varied as illustrated by the following examples:

Example 1

Where only a short time of contact of oxygen 55

and spent doctor is required for regeneration of the doctor solution, the spent doctor solution is only run through the mechanical mixer once. The liquid and any foam that may have been formed is drained off continuously to the settling tank. The doctor solution in the settling tank being regenerated is drained off and the lead sulfide that settles out is returned to the system, and on mixing with a fresh quantity of spent doctor solution it is regenerated.

10 *Example 2*

Where only a short time of contact of oxygen in spent doctor is required but excessive foaming takes place, the spent doctor solution is circulated through the mechanical mixer and foam continuously withdrawn. The foam on settling breaks to form a liquid layer of regenerated doctor solution and a solid layer of powdered lead. The lead sulfide is separated from the regenerated doctor solution and returned to the system for further treatment.

15 *Example 3*

20 Where a longer period of time of contacting oxygen and spent doctor solution is required for regeneration of the doctor solution, the spent doctor solution is continuously circulated through the mechanical mixer. A liquid and any foam that may have formed is continuously removed to the settling tank and recirculated through the mechanical mixer until a regenerated doctor solution is obtained.

25 *Example 4*

30 Where a longer period of contacting oxygen and spent doctor solution is required for regeneration and excessive foaming takes place, the spent doctor solution is circulated through the mechanical mixer and the foam that is formed removed to the settling tank. The foam in settling breaks down to a liquid layer and a solid layer of powdered lead sulfide, which are both returned to the mechanical mixer until a regenerated doctor solution is obtained.

35 It has been found in using a regenerating unit of 6 gallons capacity with a settling tank, that it is possible to regenerate from 15 to 30 gallons per hour of the spent doctor solution and at the same time increase the lead content of the doctor solution from about .01 pound per gallon to approximately .12 pound per gallon in one hour.

40 In this process it has been found that the lead is more rapidly oxidized due to the rapid circulation which keeps the lead sulfide in suspension and thereby aids oxidation. On account of the rapid circulation, the liquid can carry large percentages of solids, 10 to 20% in suspension and thereby greatly increases the conversion of lead sulfide to lead oxide.

45 The foregoing description is merely illustrative, and various changes may be made with the scope

of the appended claims, in which it is our intention to claim all novelty as broadly as the prior art permits.

5 We claim:

1. A process for regenerating spent doctor solution which comprises introducing said solution, together with lead sulfide, into a regenerating zone, introducing a large volume of oxygen-containing gas into said solution in said zone while vigorously agitating the mixture whereby a large quantity of foam is produced, withdrawing all of the regenerated doctor solution and the foam from the upper part of the said regenerating zone exclusively and conducting it to a zone of larger capacity in which the foam breaks allowing lead sulfide contained therein to settle to the bottom of said second zone and returning the lead sulfide to the regenerating zone.

10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300

1. A process for regenerating spent doctor solution which comprises introducing it, together with lead sulfide, into a regenerating zone, introducing oxygen-containing gas into the mixture while thoroughly agitating the same whereby a large quantity of foam is produced, removing all of the foam and regenerated doctor solution as they are formed from the upper part only of said regenerating zone into a settling zone in which the foam breaks and allows lead sulfide to settle, returning the lead sulfide to the regenerating zone and removing the regenerated doctor solution from said settling zone.

2. A process for regenerating spent doctor solution which comprises continually passing a mixture of said solution, together with lead sulfide, through a regenerating zone, introducing oxygen-containing gas into said mixture and mechanically agitating the same vigorously while it is in said zone whereby a large quantity of foam is produced, passing said mixture, together with all the foam produced from the upper part of said regenerating zone exclusively, into a separating zone in which the foam breaks, and recycling a slurry of doctor solution and lead sulfide to said regenerating zone.

3. A process for regenerating spent doctor solution which comprises introducing a mixture of spent doctor solution and lead sulfide in the proportion of approximately 50-90% spent doctor solution to approximately 50-10% lead sulfide, into a regenerating zone, introducing air into the regeneration zone, vigorously agitating the mixture of spent doctor solution and lead sulfide thereby securing intimate contact between the air and said mixture and producing large quantities of foam, conducting all of the foam and doctor solution from the upper part of the regenerating zone exclusively, into a separate settling zone where the foam is permitted to break and the suspended lead sulfide settles, and recycling the lead sulfide to the regenerating zone.
